[57] CLAIM

The ornamental design for a drumstick, as shown and described.

DESCRIPTION

FIG. 1 is a perspective view of a drumstick showing my new design;

FIG. 2 is a plan view taken in the direction of arrows 2—2 in FIG. 1; and

FIG. 3 is a plan view taken in the direction of arrows 3—3.

The characteristic feature of my design is the taper of slightly less than one third of one end of the thickset stick.
